UNITED STATES PATENT OFFICE.

FREDERICK G. DAWSON, OF DETROIT, MICHIGAN.

ELECTRIC FORGING AND HEAT-TREATING FURNACE.

Application filed January 11, 1921. Serial No. 436,617.

To all whom it may concern:

Be it known that I, FREDERICK G. DAWSON, a citizen of the United States, and a resident of Detroit, in the county of Wayne and State of Michigan, have invented a new and Improved Electric Forging and Heat-Treating Furnace, of which the following is a full, clear, and exact description.

This invention relates to an electric forging and heat-treating furnace, and has for an object the provision of a simple and efficient furnace structure wherein the electrodes co-operate to produce the desired amount of heat without the establishment 10 of a free burning arc, whereby the need for complicated automatic controllers is eliminated.

Another object resides in the provision of simple and easily operable means whereby 20 when the furnace is connected to an alternating current system the various electrodes in the different phases may be balanced in a simple and ready manner with respect to the current flowing in each electrode.

25 A further object resides in the arrangement of the electrodes with respect to the charge to be heated, whereby the charge is uniformly and quickly heated.

A still further object resides in the particular construction and arrangement of parts hereinafter described and claimed and shown in the accompanying drawings.

In general, the invention comprises an electric furnace structure the walls of which 35 may be made of any suitable heat-resisting and insulating material within which are contained a plurality of electrodes, one of which is a common electrode resting upon blocks and thereby spaced from the floor of 40 the furnace, the others of which rest by gravity on the common electrode and are each connected to different phases of an alternating current system, the common electrode being connected to the neutral wire 45 by said system. The contact between the common electrode and the other electrodes is regulated by the provision of a plurality of weights or other similar operating devices, whereby the pressure of contact may 50 be varied. In a single-phase system only one movable electrode need be used.

The invention is illustrated in the drawings, of which—

Figure 1 is a vertical longitudinal section of the furnace; and

55 Figure 2 is a transverse section taken on the line 2—2 of Figure 1.

The form of furnace shown in the drawings, which represents merely a preferred embodiment of my invention, comprises an inner lining wall 1 of any suitable material having high refractory properties, such as a compound of carbon and silicon and aluminum oxide. Surrounding this is an intermediate wall or lining composed of a fairly 60 good refractory material, such as corondite or bauxite. Surrounding this wall is an outer wall 3 of refractory material of any suitable composition containing silicon. A 65 casing 4 of sheet iron encloses these various 70 refractory walls.

Within these walls there is a heating chamber 5. Extending downwardly into this chamber from the upper face of the furnace are a plurality of vertical electrodes 6. 75 These electrodes pass through suitable openings in the above-mentioned walls and are surrounded by a cooling jacket 7, which may be of any suitable type and connected to a source of cooling fluid, and by a packing 80 box 8 of any suitable design which may be filled with suitable material to prevent the leakage of gas to or from the furnace. The upper ends of the electrodes 6, extending 85 above the furnace, are connected to a collar 9 to which a cable 10 is attached. This cable passes over pulleys 11 and 12 and supports at its other end a weight 13. Within the furnace the lower faces of the electrodes 6 are adapted to rest upon an electrode 14 90 which is in the form of a block of carbon, or other suitable material, extending lengthwise down the middle of the chamber 5 and supporting and engaging with the lower faces of the electrode 6. This common elec-

95 trode 14 is supported from the floor 15 of the furnace by means of a plurality of spacing bricks 16 which are made of any suitable highly refractory material. These bricks support the electrode 14 and space it above 100 the floor 15 a desired distance. The material to be heated is introduced into the fur-

nace through a lateral opening 17 and placed in position beneath the electrode 14.

Extending beneath the floor 15 of the furnace is a sheet-metal plate 18 which is connected to the neutral wire of a polyphase system, each of the electrodes 6 being connected to a different phase of the system.

In the operation of the device, when the above mentioned connections are made the poor contact between the lower face of the electrodes 6 and the upper face of the electrode 14 causes a heating action to take place. This causes the electrode 14 to heat up, and this heat is transmitted to the material beneath this electrode. The regulation of the various electrodes to balance the current in each of the phases may be effected by the adjustment of the weights 13 to vary the contact pressure between the electrodes 6 and 14. It will be noticed that the metal is heated by radiation and not by the heat of an arc. The ends of the furnace can be removed in any suitable manner so as to restore the linings and repair the parts if necessary. Because of the fact that there is a very poor circulation of air in the furnace through the lateral opening 17, and that the electrode 14 becomes white hot, the atmosphere will be a reducing one. The inner lining of a compound of carbon and silicon tends to efficiently retain the heat, whereby a high temperature can be maintained and rapidly reached by this furnace.

A consideration of the above mentioned description will show that the operation of this furnace depends merely upon a poor contact between two electrode surfaces, and not upon a free burning arc, which requires complicated apparatus to regulate. The regulation of the current in this furnace is a comparatively simple matter. A high tem-

perature is maintained with a voltage in the neighborhood of 40 volts, and in a furnace the structure of which is extremely simple.

What I claim is:

1. An electric furnace comprising a heating chamber, a common electrode within said heating chamber, a plurality of other electrodes extending into the chamber and bearing upon a surface of the common electrode, the other electrodes bearing on the common electrode by reason of their weight, and means for adjusting the pressure between the common electrode and the other electrodes. 45 50

2. An electric furnace comprising a heating chamber, a horizontally extending electrode disposed above the floor of the furnace, a plurality of vertically extending electrodes bearing by reason of their weight on the upper surface of the horizontally extending electrode, and means for adjusting the contact pressure between the vertical and horizontal electrodes, the space between the horizontal electrode and the floor of the furnace 65 forming a chamber for the charge to be heated. 60

3. An electric furnace comprising a heating chamber, a plurality of walls of refractory material surrounding said chamber, a horizontally extending electrode within the chamber and spaced above the floor thereof, a plurality of vertically extending electrodes bearing upon the upper face of the horizontal electrode by reason of their weight, and 70 means for adjusting the contact pressure between the horizontal and the vertical electrodes, the space between the horizontal electrode and the floor of the furnace serving as a chamber for the material to be heated. 75

FREDERICK G. DAWSON.
